UNITED STATES PATENT OFFICE.

NICHOLAS D. WHALEN, OF ATTLEBORO, MASSACHUSETTS, ASSIGNOR TO EUGENE C. HEALY, DOING BUSINESS AS J. T. HEALY & SON, OF ATTLEBORO, MASSACHUSETTS.

DESIGN FOR A BRACELET CHAIN OR SIMILAR ARTICLE.

Application filed January 12, 1928. Serial No. 24,841. Term of patent 3½ years.

To all whom it may concern:

Be it known that I, NICHOLAS D. WHALEN, a citizen of the United States, residing at Attleboro, in the county of Bristol and State of Massachusetts, have invented a new, original, and ornamental Design for a Bracelet Chain or Similar Article, of which the following is a specification.

Figure 1 is a side view of the chain showing my new design.

Figure 2 is a perspective view with one of the links shown cut transversely.

I claim:

The ornamental design for a bracelet chain or similar article, as shown.

NICHOLAS D. WHALEN.
